UNITED STATES PATENT OFFICE.

ABRAHAM KRAKAUER, OF NEW YORK, N. Y.

SELF-LOCKING SPRING.

Application filed December 12, 1923. Serial No. 680,086.

To all whom it may concern:

Be it known that I, ABRAHAM KRAKAUER, a citizen of the United States, residing at the city of New York, in the county of 5 Kings and State of New York, have invented certain new and useful Improvements in Self-Locking Springs, of which the following is a specification.

This invention relates to spring seats for 10 furniture and particularly to the means for locking the seat springs in place.

It is usual in furniture seats to provide a metal cross bar hung from the frame of the piece of furniture for the purpose of 15 supporting a row of the springs which make up the seat.

The means heretofore used for securing the springs to said cross bar have proven unsatisfactory, in that a number of said 20 springs often become disengaged from the support therefor, and are consequently lost or displaced either in transit, in handling or in use.

It is one of the objects of my invention to 25 provide simple but efficient means for locking a seat spring in place against displacement or removal.

A further object of this invention is the 30 provision of self locking means capable of rapid and economical manufacture and assembly for effectively securing a spring to a bar.

A still further object of this invention is 35 the provision of means for locking a spring in position at any desired point in a cross bar.

To attain the aforesaid and other objects as will appear in the description which follows, I employ the arrangements and combinations of parts shown in the preferred 40 forms in the accompanying drawings, in which—

Fig. 1 is a front elevation of the preferred 45 form of my invention showing a cross bar with a number of springs secured thereto.

Fig. 2 is a bottom plan view of the same.

Fig. 3 is a front elevation, similar to 50 Fig. 1, illustrating the manner in which the springs may be secured to the cross bar at any desired point thereof.

Fig. 4 is a front elevation showing a modified form of the spring locking means.

Fig. 5 is a vertical section of the same on the line 5—5 of Fig. 4.

Fig. 6 is a view similar to Fig. 4, showing another modified form.

Fig. 7 is a bottom plan view of the same, and Fig. 8 is a front view of still another form of spring locking means.

In the practical embodiment of my invention, the cross bar 10 is suitably hung from the frame of a piece of furniture in the usual manner as by means of the flanges 11 and 12 at the ends of said cross bar.

I prefer to make the cross section of said cross bar 10 substantially in the form of an inverted blunt V, two of the sides of said V forming the webs of said cross bar while the blunt top of said inverted V forms the flange thereof.

A series of coil springs 14 of the usual type is secured to said cross bar and it is the means for and the manner of securing said springs to the cross bar which is the subject matter of this invention.

At those points in the cross bar where it is desired to secure each of the springs 14, a hole as 15 is made in each of the webs 16. Said holes are preferably arranged in pairs, one pair for each spring, and are preferably of greater diameter than that of the wire of which the springs 14 are made. To provide for flexibility in the arrangement of the springs on said cross bar, an entire series of holes 15 may be made in pairs in said cross bar at suitable intervals as may be found by experience to be desirable, so that the springs 14 may be spaced when desired, more or less closely together, or at various and varied distances from the center of the cross bar as may suit the purposes of the purchaser. It will be understood that the holes 15 are preferably oppositely disposed in pairs in opposite webs, that only one pair of said holes is utilized for each of the coil springs 14, and that other suitable types of apertures may be used for this purpose.

It having been decided at which points in the cross bar a spring 14 is to be placed, the end 17 of the lowermost coil of said spring is passed through a pair of holes 15. In the preferred form of my invention, the end 17 of the last coil is preferably bent upwardly, so that when the spring is rotated into its final position through the holes 15, (Figs. 1 and 2), said upwardly projecting end 17 is sprung into self locking position between the webs 16, and forms an obstruction to the removal of said spring 14 in any direction.

The depression of the end coil in a direction axially of said spring below its nor-

mal position produces a tendency in said end coil to rise under the tensile stress put thereon, and thereby causes the end 17 to be pressed upwardly into firm contact with the 5 bottom edge 21 of the web. Said tendency also causes the next higher coil of the spring to be drawn downwardly into contact with the top flange of the cross bar, whereby the 10 spring is properly supported in a position wherein only contractile movement thereof is possible and wherein it is best adapted to take any pressure put thereon without danger of rotative or other movement thereof relatively to the cross bar.

15 It will be seen that a vertical pull upon the spring 14 cannot affect that portion of said spring below the holes 15; that compression of said spring 14 merely insures the engagement of that coil directly above the 20 top of the cross bar 10 with said cross bar again without affecting the remainder of the spring below the hole 15; and that rotary or twisting movement of the coil spring 14 merely causes the bent end 17 to move if at 25 all a comparatively small distance in the space between webs until the opposite web is reached, whereupon further movement is again obstructed when the end 17 engages the under surface of the other web. It will 30 be noted that that part of the last coil below the holes 15 tends to rise into its normal position and thereby insures the locking action by resisting any effort to lower the end 17 and carry said end to the outside 35 of the cross bar.

In the modified forms of my invention, shown in Figs. 4 and 7 inclusive, the upwardly bent portion 17 is dispensed with and the end 18 of the coil spring passed underneath a downwardly bent prong as 19 struck out from the web 16. In that form of my invention shown in Figs. 4 and 5 said prong 19 prevents the end 18 from rising and serves to lock said end firmly in place. It 40 will be seen that when the end 18 is sprung under the prong 19 the spring is locked not only at the end thereof, but throughout its entirety in that form of my invention shown in Figs. 6 and 7; the end 18 of the last coil 45 of the spring is sprung not only underneath the prong 19 but is passed also through the web 16 into contact with the inner or under surface of said web.

50 It will be noted that that portion of the coil spring which has passed through the holes 15 is preferably depressed below its normal position and the tendency thereof therefore is to spring upwardly in close contact with the under side of the prong 19.

55 In that form of my invention shown in Fig. 8, the end 18 of the spring terminates in a downwardly bent portion 22. Said end 18 instead of being depressed by being pulled downwardly as in Figs. 1 to 7 is 60 raised upwardly out of its normal place,

and is sprung about the top of the cross bar 10, the tendency of said end 18 to return to its normal position causing said spring 14 to become firmly locked in place. It will be seen that the springs are entirely self locking since all that is necessary to lock one of said springs into place is the insertion of the end through a pair of holes 15 and then turning said spring while depressing or raising the end until axially of the spring 75 said end snaps into position in engagement with the web or the prong. It will also be seen that the springs may be rapidly and economically assembled and once assembled are self locking against removal by attempted movement in any direction by reason of the automatic engagement of the 80 spring end under pressure with that part of the cross bar with which it is in contact.

85 I claim:

1. In a spring seat, a cross bar having apertures therein, comprising a pair of webs and a flange connecting said webs, a coil spring, and a lowermost coil on said spring having a portion thereof passed through the 90 apertures in said bar and forced in the direction of the axis of said spring away from the position said portion would normally assume if free into axially sprung engagement with one of said webs, whereby that 95 part of said coil above and not passed through said apertures engages said flange under pressure.

2. In a spring seat, a cross bar comprising a pair of upwardly converging webs having oppositely disposed holes therein near the top thereof, a flange joining the upper extremities of said webs, a coil spring, a lowermost coil on said spring comprising 100 a portion passed through a hole in each of said webs, and an upper portion above said holes adapted to be supported by the top of said flange, said portion passed through said holes being pulled under stress 105 axially of said spring out of the normal position thereof and maintained in engagement under pressure with the web of said cross bar.

110 3. In a spring seat, a cross bar having a pair of oppositely disposed holes near the top thereof, and comprising a pair of webs and a flange connecting said webs, and a coil spring having a lowermost portion 115 passed through said holes and self-maintained in engagement with the web of said cross bar under tension axially of said spring, said lowermost portion passing underneath the lowermost edge of said web, and an upwardly bent end at the end of said 120 lowermost portion disposed between said webs for limiting rotative movement of said spring relatively to said bar.

125 4. In a spring seat, in combination with a coil spring, apertured means for supporting said spring, and means for causing said 130

spring to lock itself in place comprising an end in said spring passed through the apertures in said supporting means, and forced axially out of and self maintained out of the position said end would assume if free, and in axially sprung engagement with said supporting means.

5. The method of causing a coil spring

to lock itself into place comprising the insertion of the end of said spring through a pair of holes in a cross bar, and then forcing said end in a direction axially of said spring out of the position same end would normally assume if free, and into axially sprung engagement with said cross bar.

ABRAHAM KRAKAUER.
